DESIGN FOR A FIRE EXTINGUISHER BRACKET

Carl O. G. Wittig, Golden, Colo.

Application December 15, 1933, Serial No. 50,088

Term of patent 3½ years

To all whom it may concern:

Be it known that I, CARL O. G. WITTIG, a citizen of the United States of America, and a resident of Golden, Jefferson County, Colorado, have invented a new, original, and ornamental Design for a Fire Extinguisher Bracket, of which the following is a specification, reference being had to the accompanying drawing, forming part thereof,

Figure 1 is a front elevation of the new fire extinguisher bracket. Figure 2 is a side elevation of the showing of Figure 1. Figure 3 is a bottom plan view of the showing of Figure 1. Figure 4 is a top plan view of the showing of Figure 1.

I claim:

The ornamental design for a fire extinguisher bracket, as shown.

CARL O. G. WITTIG.
